ATTORNEY

UNITED STATES PATENT OFFICE

GEORGE W. TURPIN, OF CLEVELAND, OHIO.

DEVICE FOR PRODUCING WAVES IN THE HAIR.

Application filed February 20, 1922. Serial No. 537,915.

To all whom it may concern:

Be it known that I, GEORGE W. TURPIN, a citizen of the United States, residing at Cleveland, in the county of Cuyahoga and 5 State of Ohio, have invented new and useful Improvements in Devices for Crimping or Producing Waves or Wave Ridges in the Hair.

More particularly my invention relates 10 to devices of the above character in the shape of a headgear.

Among the objects of my invention are 15 the following:—

To provide a cap or similar head covering with cords along the inner walls for producing a wave or crimp, or other suitable impression on the hair;

To provide other details of improvement tending to increase the efficiency and ser- 20 viceability of a device of the above character.

To accomplish the foregoing and other useful ends, my invention comprises means hereinafter more fully set forth and claimed.

Referring to the accompanying drawing, 25 the figure is a perspective view of the headgear of my invention, a section thereof being removed to more clearly illustrate the same.

More particularly, the body, A, may be 30 made of any suitable woven material or of any suitable flexible material, that will stretch over and hug the scalp tightly. Around the outer rim of the device, I provide a flexible band, B, which is sewed or 35 otherwise secured to the body, A. This band terminates in two loose ends, C and D, to the latter of which is secured a buckle, as shown. The end, C, is provided with a series of perforations for engaging the 40 buckle. By this means, the device may be strapped in position after having been drawn tightly over the head. On the inside of the headgear, I provide a series of flexible cords, 45 which have their terminals, 3, permanently secured to the body of the cap under

the belt. Along the length of each cord, I provide loop attachments, 4, which while they hold the cords in position, permit the portions of the cord intermediate of the ends, 3, to slide and adapt themselves to the 50 tension of the body, A.

It will be seen that after the hair is suitably smoothed out, and after it has been prepared in any suitable manner, the device of my invention may be strapped over the head 55 and left there for any suitable length of time, giving the hair time to dry and set. Thereafter the cap may be removed with a result that the hair retains the crimps or waves imparted to it by the device. It will 60 be understood, that if desired, the body, A, may be made with perforations. It will be understood, that the cords that I use may be varied as to their configuration. I do not wish to limit myself as to the cords being 65 necessarily round inasmuch as flat strips may be used if desired.

What I claim as my invention is:—

1. A head gear, a flexible body, and a series of flexible cords distributed along the 70 inner side of the body whereby waves may be impressed on the hair.

2. A head gear, a flexible body, and a series of flexible cords distributed along the inner side of the body whereby waves may 75 be impressed on the hair, said cords having their ends permanently fixed to the body, and the intermediate portions slidably secured to the body.

3. A head gear, a flexible body, and a 80 series of flexible cords distributed along the inner side of the body whereby waves may be impressed on the hair, and a belt and buckle along the rim of the headgear for clamping it to the head.

In witness whereof, I have hereunto subscribed my name this 7th day of February, 1922.

GEORGE W. TURPIN.
